OIL BURNER

Albert L. Muren, Dearborn, Mich.

Application August 28, 1937, Serial No. 161,493

12 Claims. (Cl. 261—83)

This invention relates to improvements in oil burners. It is an object of the invention to provide an oil burner wherein oil and air pass into a pump by which they are mixed and from which they are discharged under pressure through a burner nozzle having an orifice provided around it through which secondary air is discharged.

Another object of the invention is to provide an oil burner unit consisting of a motor, a fan and a pump arranged in line and housed within a casting through which air passes to the fan through the motor, and from the fan through an orifice arranged around the burner nozzle.

Another object of the invention is to provide an oil burner unit wherein a pump, from which air and oil are discharged under pressure, is located some distance behind the nozzle to insure that the mixture of oil and air passes from it to the nozzle in a state of atomization, without fear of it becoming vaporized.

A further object of the invention is to provide an oil burner wherein a mixture of oil and air is discharged from the pump under pressure, and is further atomized prior to its discharge from the nozzle to insure its ultimate delivery in the form of an excessively fine spray.

Having thus briefly stated some of the objects and advantages of the invention I will now describe it in detail with the aid of the accompanying drawings, in which:

Figure 1 illustrates a longitudinal section of the invention.

Figure 2 is an enlarged view of the cap or nozzle, with a portion thereof broken away.

Figures 3 and 4 are sections on the lines 3—3 and 4—4 of Figure 1, the section shown in Figure 3 being enlarged.

Figure 5 is an enlarged detail, and

Figure 6 is a partial longitudinal section showing a slightly modified arrangement.

Referring now to Figures 1 to 5 of the drawings, 1 designates a motor having a shaft 2 connected to, and in the present instance integral with, the shaft 3 of a fan 4. The latter consists of a hub 5 having a radial plate 7 projecting therefrom on its side remote from the motor 1, and a plurality of blades 6 extending laterally from the plate 7 opposite but spaced from the said hub. Connected to the fan shaft 3 and in this case integral with it is the shaft 8 of a pump 9. The latter may be of any preferred type though in this case a rotary pump is shown. Extending from the pump shaft 8 and driven thereby is a spindle 10.

Fastened upon the face of the pump 9 remote from the motor 1 is a housing 11 which extends

concentrically around the spindle 10 and terminates at its outer extremity in an enlarged annular head 12 which is threaded externally at 13 from its outer extremity and back of the said threaded portion an outwardly projecting flange 14 is provided. Formed in the outer end of the bore of the housing 11 is a conical opening 15 of greatest diameter at its outer extremity. A cap 16, which constitutes the burner nozzle, is in threaded engagement with the external thread 10 on the head 12 and bears against the flange 14. 17 denotes a disc which rests in a circular recess 18 formed in the inner face of the cap 16; this disc is mounted for rotation with and upon the spindle 10. In the present instance a hub 19, 15 which is formed integral with the disc 17, is mounted upon the outer end of the spindle. Adjacent the disc 17 an annular step 20 of increased diameter is provided around the hub 19 to retain a conical rotor 21 fixed upon the latter spaced 20 from the said disc. The rotor 21 rotates freely in the conical opening 15 and has a plurality of slots 22 formed across its periphery thereby leaving a plurality of tooth-like projections between them.

Formed through the disc 17 are a plurality of small openings 23 located opposite some of the rotor slots 22; these openings preferably extend through the disc parallel with the axis of the latter. Formed through the cap or nozzle 16 are apertures 24 which, as the disc 17 rotates, come into registry with the openings 23. The apertures 24 are, in the present case, shown forwardly and outwardly inclined to the cap axis, and should exceed in number the openings 23. The openings 23 may be provided at two different radial distances from the disc axis to register with apertures 24 also located at two different radial distances from the axis of the cap or nozzle 16. In Figure 1 this is clearly shown and it will also be noted that the outward inclination of the outer apertures 24 is less than that of the inner apertures. Consequently the air and oil mixture discharged through these apertures follows substantially along the lines indicated at A and C and then meets at D.

A casing 25 surrounds the motor 1, fan 4, pump 9, and housing 11, and has inwardly directed ribs 26 which support the said motor. Formed through the casing adjacent the motor 1 and preferably through the end thereof are 50 suitable air inlets such as the louvres 27. Extending inwardly from the casing 25 in close proximity to the sides of the fan blades 6 adjacent the motor 1 is a ring 28 the inside diameter of which is substantially the same as that of 55

the inside diameter of the fan blades. At its front extremity the casing 25 terminates in a circular orifice 29 which projects slightly in front of the cap or nozzle 16 and is coaxial therewith.

5 30 and 31 denote oil and air pipes which have suitable valves at 32 and 33 respectively. These pipes 30 and 31 are both connected to an intake pipe 34 to the pump 9, and the discharge from the latter passes into the interior of the housing 11 as through a pipe 35 which terminates in the latter. I also prefer to connect a pressure gauge 36 to the discharge side of the pump 9 as by a tube 35a.

10 40 denotes a series of breaker or baffle plates which may be also employed upon the spindle 10. 15 Each of these plates has a plurality of peripheral slots or openings 41 formed therein which are preferably arranged in staggered relation to the openings in the adjacent plates. These plates are of course mounted upon the spindle 20 for rotation therewith.

The operation of my oil burner is briefly as follows: The valves 32 and 33 are so set that oil and air in their desired proportions pass through the intake 34 into the pump 9 wherein 25 the oil and air are thoroughly mixed, and from which this mixture is discharged under pressure into the housing 11. The purpose of the gauge 36 is to enable the operator to maintain the desired pressure upon the mixture through regulation of the said valves. Atomization of the oil is then rendered more complete, that is the particles of oil are more finely broken up by the rotor 21 as the mixture passes through the slots 30 22. After leaving the latter the mixture passes between the rotor and the disc 17 and into the disc openings 23 from which it escapes as the disc rotation brings the said openings into registry with the cap apertures 24.

40 The breaker or baffle plates 40 may be employed when a very fine mixture is desired, or when a relatively large proportion of oil to air is to be used. Their function is to impede the natural tendency for some of the oil to travel 45 along the bore of the housing 11 to the rotor 21 and consequently to cause more thorough atomization of the oil prior to its arrival at the disc 17.

Air enters the casing 25 through the louvres 27 and passes through the motor 1 to cool it, and thence to the fan 4 from which it is discharged by the blades 6 around the periphery of the plate 7 and through the orifice 29. Thus a secondary air supply is furnished which is discharged around the mixture ejected from the cap or nozzle 16. Due to the inclination of the cap or nozzle apertures 24 the mixture is thrown into the secondary air at some little distance from the burner. Moreover when two sets of apertures 24 spaced at different radial distances from the nozzle axis are utilized as herein shown, due to the greater weight of the oil a higher percentage of oil is ejected through the outer set of apertures in the mixture discharged therethrough, and this mixture is again broken up by the mixture discharged through the inner set of apertures wherein the percentage of air is higher.

In the modification shown in Figure 6 the spindle 15a is made tubular at least intermediately of its length. This spindle is a running fit 70 in the housing 11a for the greater portion of its length. Intermediately the housing is of enlarged diameter as shown at 11b to provide an annular chamber around the spindle 15a. Connected to the enlarged housing portion 11b is the

discharge pipe 35 from the pump, and formed radially through the spindle 15a within the said chamber are a plurality of holes 15b. The front extremity of the spindle 15a terminates in a solid portion 15c of reduced diameter to receive the hub 19 of the disc 17; and formed through the front wall of the tubular portion of the spindle 15a are outlet passages 15d which open into the housing 11a immediately behind the rotor 21. When this form of construction is employed 10 larger particles of oil come into contact with and travel along the bore of the spindle 15a so that when they arrive at the outlet passages 15d they are in the form of a very thin film which is immediately broken up by the lighter fuel mixture 15 passing through the said passages.

While in the foregoing the preferred embodiments of the invention have been described and shown, it is understood that the invention is susceptible to such alterations and modifications as 20 fall within the scope of the appended claims.

What I claim as my invention and desire to secure by Letters Patent is:

1. An oil burner unit comprising a housing terminating in an apertured nozzle, a pump from 25 which a mixture of oil and air under pressure is discharged into the housing, a rotary spindle in the housing, means operating the pump and turning the spindle, and a disc fixed on the spindle and bearing against the inner face of the nozzle, said disc having openings therethrough which, as the disc rotates, register intermittently with the nozzle apertures.

2. An oil burner unit comprising the combination set forth in claim 1, wherein the number of nozzle apertures materially exceeds the number of disc apertures.

3. An oil burner unit comprising the combination set forth in claim 1, wherein the nozzle apertures are inclined forwardly and outwardly relative to the disc axis.

4. An oil burner unit comprising the combination set forth in claim 1 wherein the disc openings are provided at varying distances from the disc axis, each opening being adapted to register with some of the nozzle apertures which are also located at varying distances from the disc axis.

5. An oil burner unit comprising the combination set forth in claim 1, wherein both the disc openings and the nozzle apertures are provided 50 at varying distances from the disc axis whereby some of the openings register with each aperture, and wherein the nozzle apertures located nearer the said axis are forwardly and outwardly inclined to the axis at a greater angle than the nozzle apertures located further from said axis.

6. An oil burner unit comprising the combination set forth in claim 1, wherein a rotor having transverse slots formed therethrough is fixed on said spindle to further break up the mixture 60 passing through the housing to the disc.

7. An oil burner unit comprising the combination set forth in claim 1 wherein the outer extremity of the housing bore is forwardly and outwardly inclined, and a conical rotor the periphery 65 of which rotates freely in said inclined bore is mounted on said spindle adjacent said disc, the rotor having peripheral slots formed transversely therethrough.

8. An oil burner comprising a pump, a housing 70 projecting from one face thereof, a spindle driven by the pump shaft extending through the housing, a nozzle having a plurality of apertures therethrough mounted on the outer extremity of the housing, means for introducing oil and air 75

into the pump, means through which a mixture of oil and air under pressure is discharged from the pump into the housing, and a disc having openings therethrough adapted to register with 5 the nozzle apertures fixed on the spindle, the mixture passing through the disc openings and the nozzle apertures.

9. An oil burner unit comprising a pump from which an air and oil mixture is adapted to be 10 discharged, a housing projecting from one face thereof, a spindle extending through the housing and driven by the pump shaft, an apertured nozzle on the outer extremity of the housing, a disc fixed on the spindle for rotation against the inner 15 face of the nozzle, said disc having openings therethrough adapted to register with the nozzle apertures as the spindle rotates, a rotor in said housing fixed on said spindle, and means through which the oil and air mixture discharged from 20 the pump is introduced into the housing.

10. In an oil burner unit comprising the combination set forth in claim 1, wherein the spindle is tubular intermediately of its length, said intermediate spindle portion rotates freely in its housing, the latter has an enlarged portion wherein 25 an annular chamber is formed around said tubular spindle portion, the latter being apertured said apertures opening into said chamber, the oil and air mixture passing from the chamber into the

spindle, other openings through the spindle adjacent the disc for the passage of the mixture thereto, and the discharge from the pump passing into said chamber.

11. An oil burner unit comprising a pump from 5 which a mixture of oil and air is discharged under pressure, a housing into which said mixture is discharged, a rotary spindle extending through the housing, means driving the pump and turning the spindle, an apertured nozzle on the housing, and a perforated element on the outer extremity of the spindle rotatable therewith adjacent the nozzle through which the air and oil mixture discharged by the pump passes to and through the nozzle apertures as the spindle turns. 10 15

12. An oil burner unit comprising a housing terminating in an apertured nozzle, a pump from which a mixture of oil and air under pressure is discharged into the housing, a rotary spindle extending through the latter, a plurality of spaced 20 plates having peripheral slots formed therethrough mounted on the spindle for rotation therewith within the housing adapted to break up the mixture more finely, a perforated element carried by the spindle, said perforations being 25 adapted to register with the nozzle apertures as the spindle rotates to permit discharge of the mixture.

ALBERT L. MUREN.
